Robert W. Randle.

UNITED STATES PATENT OFFICE.

MARY A. NICHOLS, OF BLOOMINGPORT, INDIANA.

THREAD-CUTTER.

SPECIFICATION forming part of Letters Patent No. 671,224, dated April 2, 1901.

Application filed October 11, 1900. Serial No. 32,777. (No model.)

To all whom it may concern:

Be it known that I, MARY A. NICHOLS, a citizen of the United States, residing at Bloomingport, in the county of Randolph and State 5 of Indiana, have invented new and useful Improvements in Thread-Cutters; and I do hereby declare the following to be a full, clear, and exact description of the invention, such as will enable others skilled in the art to which 10 it appertains to make and use the same.

This invention consists in an improved thread-cutter and in the arrangements and combinations of the parts of the same, all substantially as will be hereinafter set forth 15 and finally embraced in the claims and as fully illustrated in the accompanying drawings, forming a part of this specification.

One object of my present invention is to provide a thread-cutter that can be worn on 20 the clothing of a person, so as to be easy of access to the operator.

Another object is to provide a thread-cutter simple in construction, useful, and at the same time ornamental.

25 Another object is to provide a thread-cutter with which a thread can be quickly and easily severed and which will not be in the way of the person using it; and still another object is to provide a new article of manufacture in a thread-cutter that can be made and sold at a very low price.

I attain these objects by the mechanism and combination of parts illustrated in the accompanying drawings, in which—

35 Figure 1 is a plan view of the shield or body of my device, showing the piece for attaching the cutter thereto. Fig. 2 is a vertical sectional view of the shield or body, taken on the line X X of Fig. 1, and a side view of the 40 parts to be attached to the shield A. Fig. 3 is a cross-sectional view of the parts shown in Figs. 1 and 2, taken on the line z z of Fig. 1. Fig. 4 is a side view of the knife C, and Fig. 5 is a plan view of the guard B opened 45 out.

Similar letters of reference denote similar parts throughout the several views.

Referring now to the drawings, the shield or plate A is the base or body of my device, 50 through which two oblong holes D are made for the purpose of securing the guard B thereto. The guard B is cut out of one piece of

material in substantially the form shown in Fig. 5. Each half is then bent back on the line O O parallel with each other, with a slight 55 distance between them, to form a slot for the knife C and of sufficient size therefor. The four wings E are then inserted in the two holes D, and the points F are bent outward at right angles to the parts E, thus securely 60 fastening the guard D on the face of the shield A. The knife C is made of one piece of material of the form shown, with an outwardly-extending lug I at the top, and the knife C being sharpened on one edge, as at 65 K. The knife C is inserted in the top of the slot formed by the guard B and is to be pushed down in said slot until the lug I comes in contact with the top of the guard B, as shown in Fig. 2. The opening H in the guard will allow the sharp edge K of the knife C to be exposed, as shown in Fig. 2. It will be seen that the knife C can be easily removed for 70 the purpose of sharpening same.

A pin G is secured to the back of the shield 75 A for the purpose of securing the device to the clothing of a person.

It is apparent that if my device be secured to the bosom of a garment, by means of the pin G, the sharp edge K of the knife C will 80 then extend out in the proper form for the person to take hold of one end of a thread with one hand and draw the thread from the spool until a sufficient amount is drawn off and then bringing the point of the thread to 85 be severed against the knife, and that a slight downward or upward movement of the hands will instantly and easily sever the thread at the point desired, and without the necessity of touching my invention with the hands. 90

Although I have specifically shown and described the construction and relative arrangement of the several elements of my invention, I do not desire to be confined to the same, as such changes or modifications may be made 95 as clearly fall within the scope of my invention without departing from the spirit thereof.

Having thus described my invention, what I claim, and desire to secure by Letters Patent of the United States, is—

1. In a thread-cutter, the combination of a shield or base of substantially the form shown, a guard bent back upon itself with a space 100 between its two parts sufficient to receive a

knife, of the form shown, wings projecting back from each side of the guard adapted to be inserted in holes in the shield, said wings being bent outward after being inserted to 5 secure the guard to the shield, an aperture cut in the outer edge of the fold of guard to expose the knife inclosed in the guard, a knife with a cutting edge, a lug on the outer upper edge of the knife, the knife being adapted to be 10 inclosed in the folds of the guard, a pin secured on the back of the shield, all substantially as described and set forth and for the purposes specified.

2. A thread-cutter comprising a shield with 15 a knife set at right angles thereto, said knife being held in place by a guard attached to the shield, in the manner specified, a lug on the upper edge of the knife to prevent the knife from slipping through the guard, a pin

secured to the back of the shield, all as described and set forth. 20

3. The combination in a thread-cutter, of the shield or base A, of substantially the form shown, a guard attached thereto by projections from the guard extending through holes 25 in the shield and bent outward, a knife C inserted between the two parts of the guard, an aperture H in the outer edge of the guard B, a pin G for securing the device to the clothing, all substantially as shown and described 30 and for the purposes specified.

In testimony whereof I have signed my name to this specification in the presence of two subscribing witnesses.

MARY A. NICHOLS.
